United States Patent Office.

CHARLES C. SAVERY, OF PHILADELPHIA, PENNSYLVANIA.

Design No. 4,498, dated November 29, 1870.

DESIGN FOR A WATER-COOLER STAND.

The Schedule referred to in these Letters Patent and making part of the same.

To all whom it may concern:

Be it known that I, CHARLES C. SAVERY, of Philadelphia, in the county of Philadelphia and State of Pennsylvania, have invented a new and original Design for a Water-Cooler Stand; and I do hereby declare that the following is a full and exact description thereof, reference being had to the accompanying drawing making part of this specification—

Figure 1 being a front elevation of the water-cooler stand.

Figure 2, a top view of the same.

Figure 3, a vertical section of the top in a plane indicated by the line $x\ x$, fig. 2

Like letters designate corresponding parts in all of the figures.

The top A, on which the water-cooler rests, is of iron, enameled on its upper surface a .

It is mounted on a standard, B, provided with legs b , or a suitable base to sustain it.

From one side of the enameled top A a cup-holder, C, projects outward, being secured under the top by its flanch c , having a slot, d , which fits over a screw, f , projecting downward from the top, and is held by a

nut, g , or the equivalent thereof, so that it may be adjusted in position or removed.

The cup-holder may be round, oval, square, or oblong, and also is enameled on top, and the drip or waste-cup D on the inside, so that every part of the stand which is exposed to the water is protected by enamel.

The cup D is suspended under the holder C by a central rod, h , with an oblong head at its upper end passed up through an oblong opening in the holder, another turned at an angle thereto to hold the cup suspended, or by other suitable means.

The drip-cup holder may be removed from the stand, which then may be used for a table.

What I claim as my invention is—

The design for a water-cooler stand, having an enameled top, A, and drip-cup holder C, as represented and described.

CHARLES C. SAVERY.
